UNITED STATES PATENT OFFICE.

MATHEW LEANDER KING, OF AMES, IOWA.

GEAR-JIG.

SPECIFICATION forming part of Letters Patent No. 777,639, dated December 13, 1904.

Application filed December 12, 1903. Serial No. 184,958. (No model.)

To all whom it may concern:

Be it known that I, MATHEW LEANDER KING, a citizen of the United States, residing at Ames, in the county of Story and State of Iowa, have invented a new and useful Improvement in Gear-Jigs, of which the following is a specification.

The object of my invention is the sawing of gear-patterns from turned wooden blanks.

10 A further object is to save much of the time required to lay out on the blank the small end of the teeth and lining down across the face and also to save handwork on the teeth.

My invention consists of a shaft carrying 15 the wooden blank and having as a pivotal point a vertically-slotted post through which the saw-blade works, the longitudinal axis of the shaft being on a line intersecting at the pivotal point the line of the saw-teeth.

20 My invention also consists in the novel features of construction and combination of parts hereinafter described, particularly pointed out in the claims, and shown in the accompanying drawings, in which—

25 Figure 1 is a side elevation of my device, the band-saw table being in section. Fig. 2 is a plan view, the table and blank being omitted. Fig. 3 is a vertical section through the pivotal and saw-guide post. Fig. 4 is a plan 30 view of the forward portion of the base, the post being removed. Fig. 5 is a perspective view of the parts shown in plan in Fig. 4. Figs. 6, 7, 8, and 9 are detail perspective views of the various parts assembled on the base 35 shown in Fig. 5, the parts being shown detached. Fig. 10 is a perspective view of the shaft-handle partly broken off. Fig. 11 is a vertical elevation of the device as used with small and flat gears. Fig. 12 is a plan view 40 of the device as shown in Fig. 11, the gear or blank being omitted. Fig. 13 is a side elevation of an attachment for dovetailing wooden gear-teeth, the attachment being applied to the parts shown in Figs. 1, 2, 3, and 4, the 45 base and post being omitted. Fig. 14 is a perspective view of the two sections, detached, of the clamping-disk. Fig. 15 is a detail plan view of the tooth-holding clamp. Fig. 16 is a view in elevation of a slightly-modified form

of supporting-bracket. Fig. 17 is a plan view 50 of said bracket. Fig. 18 is a section on the line 18 18 of Fig. 16.

In the drawings, A represents a suitable base of any desired form and construction, which is mounted upon and bolted to the band-saw table A'. At its forward end the base is formed with a projecting boss carrying a cylindrical lug A², which has a vertical threaded bore A³ and is also diametrically slotted, as shown at A⁴, the slot intersecting the bore 60 and extending from the front face of the lug to a point to the rear of the bore A³. The saw-blade A⁵ is adapted to move horizontally in this slot, and while the blade works normally vertically in the bore A³ it is moved to 65 the rear of the bore into the slot A⁴ while the post B is being threaded into the bore A³, the post having threads cut at its lower end adapted to engage those of the said bore. This post has formed in it a vertical U-shaped slot B², 70 which extends diametrically into the post beyond the axial center of the said post. In the top of the post to one side of the slot is formed a socket B³. Over this post fits a sleeve C, flattened on opposite sides, the sleeve having 75 the cylindrical bore C', receiving the post B, and is cut or longitudinally slotted at C². On the flattened sides threaded apertures C³ are formed in the sleeve and receive the pivot-screws C⁵, which are threaded into them. The 80 height of the sleeve C is greater than the length of the non-threaded portion of the post B, and the sleeve therefore extends above the post. A washer D fits within the projecting portion of the sleeve and rests on the upper face of the post B. The washer is slotted at D' similar to the slot B² in the post, and in or from the bow portion of this slot extends a narrow supplemental slot D², corresponding 85 to the slot A⁴, and the slot D² receives the back 90 of the saw-blade and holds the same against vibration, the teeth moving vertically in the slot D'. Depending from the washer is a pin D³, which fits in the socket B³, formed in the post B, and prevents rotation of the washer. 95

A casting E is formed with the bifurcated members E', having the lining apertures E², and the bow portion is recessed, as shown at

E³. The casting has a threaded socket, (not shown,) into which is threaded the lower end of the shaft-handle E⁴.

In cutting the ordinary bevel-gear the 5 sleeve C is used; but to allow clearance for a flat cone or a very small gear I employ a sleeve F, having the pivotal point near the top and cut away on the front, as shown at F' in Fig. 11. To this sleeve is pivoted a bracket 10 G in the same manner as the casting E is pivoted, the casting being practically a form of bracket, the bracket G having the lugs G', which correspond to the bifurcated members E' of the casting-bracket. At its upper end 15 the bracket G, which is in the form of an open rectangular frame, carries a sleeve G², having a bore through which the shaft-handle E⁴ passes, and a suitable binding-screw G³ bears on the shaft, working through a boss on the 20 sleeve G².

To support the wooden blank on the shaft-handle E⁴, an adjustable collar H is fitted on the shaft and secured in its adjusted position by means of the usual set-screw, as shown 25 at H'.

In Figs. 13, 14, and 15 I have shown an attachment for holding wooden gear-teeth while being dovetailed, the attachment being carried by the shaft-handle E⁴. The attachment 30 comprises a clamp J, adapted to hold a tooth J', and two disks having contacting faces, the disk J² having a straight bore J¹³ offset from the center of the disk and the disk J³ having a bore J⁴, adapted to receive the shaft E⁴, the 35 disk J³ having also a bore J⁵ intersecting the bore J⁴. A suitable set-screw J⁶ works in the bore J⁵, which is threaded and bears at its inner end on the shaft-handle E⁴. The clamp J consists of a short section J⁷, into which one 40 end of the rod J¹⁰ is secured, and a long curved section J⁸, having a bifurcated end portion engaging the rod J¹⁰ and held to the section J⁷ by an adjustable screw or bolt. Both sections carry suitable jaws adapted to coact together 45 and hold the tooth J'. The rod J¹⁰ passes through the bore J¹³, and a set-screw J⁶ works through a bore similar to that at J⁵ and bears against the rod J¹⁰. A central aperture J¹¹ is formed in each disk, being threaded, and a 50 screw J¹⁴, passing through the disks, binds them together.

In Figs. 16, 17, and 18 I have shown a slightly-modified form of supporting-bracket consisting of the bracket K, having at one 55 end a curved portion on which is formed the vertical lugs K³, and at the opposite end is formed a sleeve K'. The lugs K³ correspond to the arms G' of the bracket G and the sleeve K' to the sleeve G², and the brackets are used 60 in practically the same manner. In assembling the parts the saw-blade is moved into the slot A⁴, passed to threaded bore and the post B is threaded into place. The saw-blade is then properly adjusted with the teeth on

the line of the axial center of the post B, and 65 the sleeve C is then dropped into position, holding the blade against vibration after insertion of the washer D. The casting or bracket E is then placed in position, being secured by the pivot-screws C⁵. The shaft-handle E⁴ is then threaded into the casting, the wooden blank placed in position and adjusted for the proper bevel by means of the collar H, the movement of said collar varying the 70 bevel of the teeth cut. It will be noted that 75 the longitudinal axis of the shaft E⁴ is on a line intersecting the bore of the post B and that the axial line of the bore of the post is in the line of action of the saw-teeth. The 80 point of intersection of these lines will be the apex of any gear-pattern that is being cut.

The advantages of the above-described construction will be obvious to those skilled in the art to which it appertains.

Having thus fully described my invention, 85 what I claim as new, and desire to secure by Letters Patent, is—

1. In a gear-jig, a post having a vertical slot adapted to receive a vertically-movable saw-blade, and a shaft-handle adapted to carry a 90 blank, said handle being pivoted to the post.

2. A gear-jig comprising a post having a vertical bore adapted to receive a saw-blade, a shaft-handle pivotally connected to the post, an adjustable collar carried by the said shaft, 95 and means for preventing vibration of the saw-blade, the line of the longitudinal axis of the shaft intersecting in the bore the line of the saw-teeth and giving the apex of the gear-pattern, substantially as set forth. 100

3. A gear-jig comprising a base-plate having a cylindrical lug thereon, said lug having a bore and slotted, the slot intersecting the bore, the bore being threaded, a slotted post adapted to be threaded into said bore, a sleeve 105 fitting over and extending above the post said sleeve being slotted longitudinally, a washer fitting on the post within the sleeve and slotted to receive the back of a saw-blade, said blade working through the lug and post, and a shaft-handle adapted to carry a gear-blank 110 pivotally connected to the sleeve, as and for the purpose set forth.

4. A gear-jig comprising a vertically-slotted post, a longitudinally-cut sleeve adapted 115 to fit over said post, a bracket pivotally connected to opposite sides of the sleeve, a shaft-handle secured to the bracket, the said slotted post and sleeve forming a bore adapted to receive a saw-blade, and means for adjustably securing a gear-blank on the said shaft-handle, substantially as described. 120

5. The combination with a base having a lug formed thereon, said lug having a threaded bore, a post threaded to fit the bore of the lug, the said post having a longitudinal slot extending inwardly beyond the longitudinal axial line of the post, a sleeve adapted to fit 125

over the post, a bracket pivotally connected to the sleeve, a shaft-handle carried by the bracket, a sectional disk, one section of said disk being carried by the shaft-handle, and 5 the other section being carried by the first-mentioned section, a rod passing through the second-mentioned section of the disk, and a

clamping member carried at an end of the rod, said clamping member being adapted to hold a blank.
